CHARLES J. EVERETT, OF TENAFLY, NEW JERSEY

STYLUS-ACTUATING MECHANISM

Application filed February 16, 1924. Serial No. 693,378.

The invention relates to a stylus or needle used for perforating or puncturing a record sheet to indicate by a curve made up by the perforations, the condition at different times 5 of the apparatus in connection with which the record sheet is used. For example, in my prior co-pending application Serial No. 539,382, filed February 27th, 1922, entitled Recording mechanism for vehicles, I have de- 10 scribed at length a recording mechanism adapted to be installed upon motor vehicles for the purpose of giving information as to how long the vehicle remained idle after being taken out by the driver, the periods of 15 time over which it was idle, the distance traveled and the speed at which the vehicle was operated.

The present invention relates more particularly to the mechanism which actuates 20 the stylus in similar recording mechanisms, and has for an object to provide such a mechanism which will insure that the stylus is advanced to perforate the record sheet properly on each stroke, and positively withdrawn 25 to retracted position after each perforation, thus insuring that the stylus will not stick in the record sheet, or fail to punch properly, when in use.

The invention also aims to provide an ac- 30 tuating mechanism of the above nature which will insure that the stylus is not left in ad- 35vanced or partially withdrawn position when the apparatus with which it is used, comes to rest. Thus if the record sheet is continuously driven by a clockwork, for example, the stylus will never be left stationary in a position 40 in which it would catch in the record sheet.

Another object is to provide an actuating mechanism of the above nature which will 45 function properly upon reversals in motion of the apparatus to which it is connected. For example, if the record sheet is to furnish data as to the movements of a motor vehicle, the stylus will function properly while the 50 vehicle is being backed.

Further objects and advantages of the in- 55vention will be in part obvious and in part specifically pointed out in the description hereinafter contained, which, taken in con- 60nection with the accompanying drawings,

discloses a preferred embodiment thereof. Such embodiment, however, is to be considered merely as illustrative of its principles. In the drawings:

Fig. 1 is a plan view partly in section of a recording mechanism constructed in accordance with the invention. This figure is taken on line 1—1 of Fig. 2, looking in the direction of the arrows. 55

Fig. 2 is a side elevation of the recording mechanism looking from the left of Fig. 1, 60 being a section taken upon the lines 2—2 of Figs. 1 and 3, looking in the direction of the arrows.

Fig. 3 is a front elevation of the mechanism 65 as the latter appears in Fig. 1.

Fig. 4 is a fragmentary end view looking from the right of Fig. 1.

Fig. 5 is a diagrammatic detail view showing the shape of a cam forming an element 70 of the particular embodiment of the invention which is illustrated in Figs. 1 to 4.

As the present invention is concerned more particularly with the stylus actuating mechanism of a recording apparatus, the apparatus 75 as a whole is not described or illustrated in detail herein, but may be considered as any suitable type, for example, as shown in my co-pending application above referred to, and embodying a record sheet which is moved 80 by a clockwork (not illustrated) over a plate or table 1 to be perforated by the stylus, and provided with a power spindle 2 (shown at the right of Figs. 1 and 2) for driving the stylus actuating mechanism. 85

The stylus or needle 3 (Fig. 2) may be slidably supported in a sleeve 4, the latter in the present instance being carried by an arm 5 which is pivoted to a post 6 (Figs. 1 and 2) in such manner that, as the mechanism moves, 90 the needle 3 travels back and forth underneath a slot 7 (Fig. 2) in plate 1, thus being presented to different portions of the record sheet. As shown, the arm 5 is moved back and forth as aforesaid, by means of a cam 8, 95 against which a roller 9 on the arm 5 is held by a spring 10 (Fig. 1), the cam 8 being carried by a vertical spindle 11 having a worm gear 12 driven by a worm 13 on a transverse shaft 14, which latter carries a gear 15 suitably 100

bly driven from the power spindle 2. In the present form of the invention, the gear 15 is driven by means of a small gear 16 on a spindle 16a which also drives a gear 17 loose on a shaft 23, and there are additional motion transmitting elements which will be later more specifically described.

The stylus 3 is preferably provided at its lower end with a head 18 which rests against a bearing member or plate 19 shown as pivoted to spindle 14 above described. A stop 21 (Fig. 2) is provided upon plate 19 to engage above the head 18 on the stylus and draw the latter back with the plate.

I prefer to actuate the stylus positively, so to speak, by parts having sufficient power and definite path of motion to make the stylus reliable in its perforating operation. In the present embodiment, the stylus is actuated by a cam member 22 (Figs. 2 and 3) mounted upon a spindle 23 and adapted to strike a part 24 (Fig. 3) on the under side of plate 19, and thus project the stylus through slot 7 in plate 1, and perforate the record sheet. The motion of the shaft 23 preferably is accelerated during the period in which it advances the stylus. As shown, tension spring 25 is connected between cam member 22 and a post 26, in such manner that during about one-half a revolution of shaft 23, the spring 25 is stretched to a point of dead centre on the far side of shaft 23, after which the spring turns the shaft and cam member 22 through the remainder of its revolution with an accelerated motion, and cam 22 strikes part 24 during this accelerated motion to advance the stylus a definite distance in its perforating stroke. In the present instance the shaft 23 is turned through its first half revolution above-mentioned by means of a pin 27 (Fig. 1) on gear 17 which engages behind a pin 28 on a hub 29 fixed to spindle 23. Thus as gear 17 turns, the spindle 23 and cam member 22 are rotated relatively slowly, but as spring 25 passes dead centre, the motion is accelerated through the remainder of its revolution, after which pin 27 again engages pin 28.

The stylus 3 according to the present invention is positively withdrawn from advanced or perforating position by means of a moving part having a definite path of motion and engaging the stylus during at least a portion of its cycle of motion, to withdraw the latter; thus so long as this motion is continued, the stylus will be withdrawn a definite distance after each perforating stroke. Preferably the motion of the part above mentioned, which withdraws the stylus, is derived from an independent source of energy such as a spring, in order that the withdrawal of the stylus shall not be dependent upon the continued motion of the apparatus in connection with which the stylus is used.

In the present instance the stylus 3 is withdrawn from advanced position by means of

a cam member 30 adjacent cam 22 above described, and also carried by spindle 23, the cam member 30 rotating within a yoke 31 carried by plate 19. As will be noted from Figs. 2 and 5 cam member 30 bears against the yoke 31 just after the perforating stroke of the stylus has been completed so as to positively withdraw the stylus a definite distance from the record sheet. At this time the shaft 23 and cams 22 and 30 carried thereby are being turned with an accelerated motion by spring 25 which has been previously stretched to dead center as above described; that is to say, the first part of the accelerated motion of shaft 23 as brought about by spring 25, causes cam 22 to advance the stylus, and then as such motion continues, the cam 30 engages yoke 31 and withdraws the stylus a definite distance from the record sheet. Stop 20 may be provided to engage yoke 31 and prevent the latter from dropping down farther than is necessary, while the spring 25 is being tensioned.

Thus the stylus is positively withdrawn a definite distance with a rapid motion so as not to stick in the record sheet, and even though the power spindle 2 stops moving after the stylus 3 has started to advance, the stylus will be moved to fully withdrawn position by spring 25 and there will be no danger of leaving the stylus in advanced position when its associated parts come to rest. In certain instances as where the record sheet is driven continuously by a clockwork, the stylus otherwise might come to rest in a position penetrating the record sheet so as to tear the latter.

It will be noted that during this perforating stroke the stylus 3 does not have to be advanced against the action of a spring, as would be the case if a spring were imposed between the sleeve 4 and head 18, for example; thus the spring 25 may be made as powerful as desired since the force of this spring does not have to be overcome during the advancing stroke of the stylus, but on the contrary the strength of the spring assists in producing a powerful perforating stroke. If a spring were employed in connection with the stylus 3, and compressed during the advancing stroke so as to retract the stylus by the recoil of the spring, the latter would have to be made relatively weak so as not to detract too much from the force of the perforating stroke, and would be correspondingly weak and uncertain in its action of withdrawing the stylus by recoil.

I prefer to employ in connection with the stylus actuating mechanism, devices for driving the latter in the same direction, even though the motion of the driving shaft 2 or the apparatus to which it is connected, may be reversed. In the present instance, a pair of ratchet wheels 32 and 33 are fixedly mounted upon shaft 2 and between these

ratchet wheels a pair of gears 34 and 35 are loosely mounted on said shaft, and provided with oppositely directed ratched members 36 and 37 respectively engaging gears 34 and 35.

5 Gear 35 directly engages a gear 38 fixed to spindle 16a above described, so that if power shaft 2 is turned in one direction, ratchet 37 will engage wheel 33 and shaft 16a will be rotated through gears 35 and 38. But if shaft 2 should rotate in the opposite direction, ratchet 36 will engage ratchet wheel 32, and gear 34 will turn an idler gear 39 interposed between the latter and a further gear 40 on spindle 16a, thus driving the latter in the same direction as before. It will be understood that the particular location of the reversing devices above-mentioned, is not essential.

20 While a specific embodiment of the invention has been described, it will be obvious that many changes will be made therein without departing from its principles, as defined in the following claims:

25 I claim:—

1. A mechanism for punching record sheets and the like, comprising a reciprocatory stylus adapted to perforate the sheets, and means for withdrawing said stylus from advanced position comprising a member having a positive driving mechanism associated therewith insuring a definite path of travel therefor, said member being engageable with a part moving with the stylus to retract the same during a portion of the cycle of movement of said member independently of the said driving mechanism.

2. In combination, a reciprocatory stylus, and means for withdrawing said stylus from advanced position comprising a member having a positive driving mechanism associated therewith insuring a definite path of travel therefor, said member being engageable with a part moving with the stylus to retract the same during a portion of the cycle of movement of said member, said member being moved by a spring through the above mentioned portion of its cycle.

3. In combination, a reciprocatory stylus, and means for withdrawing said stylus from advanced position comprising a member having a positive driving mechanism associated therewith insuring a definite path of travel therefor, said member being engageable with a part moving with the stylus to retract the same during a portion of the cycle of movement of said member, said member being moved by a spring through the above mentioned portion of its cycle, and being moved through a remaining portion of its cycle against the action of the spring to store up energy in the latter.

4. In combination, a reciprocatory stylus, and means for withdrawing said stylus from advanced position comprising a rotary cam

member, engageable with a part moving with the stylus to retract the same during a portion of the cycle of movement of said cam member, means for turning said cam member through a part of a revolution against the action of a spring to store energy in the latter, whereby the spring may move said cam member through the portion of its cycle in which it retracts the stylus.

5. In combination, a reciprocatory stylus, cam means movable through a definite path of travel and adapted to engage parts moving with the stylus to advance and retract the latter, mechanism for moving said cam means through a part of its cycle against the action of a spring to store up energy in the latter, whereby the spring will move said cam means through a remaining portion of its cycle to advance and withdraw the stylus with accelerated motion.

6. A mechanism for punching record sheets and the like, comprising a reciprocatory stylus adapted to perforate the sheets and means for withdrawing the stylus from advanced position, comprising a spring which urges the stylus toward retracted position only after the advancing stroke has been completed.

7. In combination, a reciprocatory stylus, a bearing member engaging said stylus, a cam member adapted to strike said bearing member to advance the stylus, driving means for said cam member, a second cam member also engaging said bearing member, and adapted to withdraw the stylus, said driving means turning said cam members through a portion of their range of movement, and a spring connected to said cam members and stretched during the above mentioned portion of their cycle of movement, said spring acting to accelerate the cam members to advance and withdraw the stylus during a remaining portion of their range of movement.

8. The combination set forth in claim 7, wherein said last-mentioned cam member engages a yoke connected to said bearing member.

9. In combination, a stylus-actuating mechanism, a driving shaft therefor, and means for driving said mechanism always in the same direction upon reversal of the direction of rotation of said driving shaft, said last-mentioned means comprising alternative sets of gears interposed between said mechanism and said driving shaft, with means depending upon the direction of rotation of said driving shaft for selectively coupling said sets of gears thereto.

10. A device of the character described, comprising a reciprocatory stylus, means for withdrawing said stylus from advanced position comprising a member having a positive driving mechanism associated therewith insuring a definite path of travel therefor, and yielding cam means engageable with a part

moving with the stylus to retract the same during a portion of the cycle of movement of said member.

11. A device of the character described, comprising a stylus, means for pivotally mounting said stylus so that its point may move in an arcuate path, a stylus actuating mechanism, a driving shaft for the mechanism, and means for driving said mechanism always in the same direction upon reversal of the direction of rotation of said driving shaft.

In testimony that I claim the foregoing, I have hereunto set my hand this 27th day of December, 1923.

CHARLES J. EVERETT.
